CLAIM

The ornamental design for a earthquake measuring desk ornament, as shown and described.

DESCRIPTION

FIG. 1 is a perspective view of an earthquake measuring desk ornament showing my new design;

FIG. 2 is a perspective view thereof, the spheres in an alternate position;

FIG. 3 is a top plan view thereof, the spheres removed for clarity of illustration;

FIG. 4 is a bottom plan view thereof;

FIG. 5 is a left side elevation view of FIG. 3, the right side being a mirror image; and,

FIG. 6 is a rear elevational view of FIG. 3, the front being a mirror image.

FIG 1

FIG 2
